(No Model.)

J. REUTERBERG.
COMBINATION LOCK.

No. 605,514.

Patented June 14, 1898.

UNITED STATES PATENT OFFICE.

JOHN REUTERBERG, OF TWO HARBORS, MINNESOTA.

COMBINATION-LOCK.

SPECIFICATION forming part of Letters Patent No. 605,514, dated June 14, 1898.

Application filed January 5, 1897. Serial No. 618,093. (No model.)

To all whom it may concern:

Be it known that I, JOHN REUTERBERG, a citizen of the United States, residing at Two Harbors, in the county of Lake and State of Minnesota, have invented certain new and useful Improvements in Combination-Locks; and I do declare the following to be a full, clear, and exact description of the invention, such as will enable others skilled in the art 5 to which it appertains to make and use the same, reference being had to the accompanying drawings, and to the figures of reference marked thereon, which form a part of this specification.

15 My invention relates to improvements in mechanism for locking chests or trunks, the object being to provide a lock that can be operated without a key and may be changed a number of times.

20 My invention consists of certain novel constructions and arrangements of parts, reference being had to the drawings, in which similar numerals of reference refer to like or corresponding parts in the several figures of 25 the drawings.

Figure 1 is a plan view of my invention, showing the same applied to a chest or trunk. Fig. 2 is a transverse sectional view on lines 2 2 of Fig. 1. Fig. 3 comprises all the different parts shown in detail outside of Figs. 1, 2, and 4. Fig. 4 shows the form of the casing into which all the different parts are placed.

30 Numeral 1 indicates the lid or cover of a chest or trunk; 2, the body of a chest or trunk; 3, the hasp or latch, extending down to engage the lock; 4, the notches, adapted to be engaged by the tumblers; 5, the dial; 6, the plate, to which the lock is secured.

7 represents the casing as set forth in Fig. 40 4, provided with lugs 8 8, which for convenience I bend over cover 32 for the purpose of securing and retaining it in its place.

9 shows a continuance or connection of casing 7; 10, the receptacles and guides for 45 rings or washers 19, 23, and 24, which are placed between tumblers 11, 15, and 20. The object of washers 19, 23, and 24 is to keep the several disks in their proper places.

11 shows the first tumbler placed in the 50 casing; 12, the central hole in tumbler 11. 13

refers to slot in said tumbler, into which the projecting point 26 extends.

14 is slot in tumbler 11, placed in position, allowing hasp 3 free ingress and egress.

15 refers to the second tumbler placed in 55 the casing, being provided with slot 18, having same purpose as slot 14. Hole 16 is the receptacle for hub 25 and circular slot 17, into which projection 26 projects, and is the means by which said tumbler is moved. 60

20 shows the third tumbler, provided with slot 23, the purpose of said slot being the same as explained about slots 14 and 18. Hole 21 serves as a receptacle for hub 25, and circular slot 22 is the means by which said tumbler 65 may be operated through the right-angular projection 26 from hub 25, hub 25 being provided with projection 27, which is adapted to engage one of the grooves 28 in the under side of operating-knob 29, which extends 70 through hub 25 and is held in place by screw and washer 35. The object of said recesses in said knob 29 is to change the combination of the lock by changing projection 27 from one recess to another in knob 29. The combination changes so that other points on the dial on said knob will indicate the correct position of the tumblers, the operating-knob 75 29 being provided on its face with certain points 30 and 31, those referred to by numerals 30 being blank, so as to distinguish them from those referred to by numerals 31, which are marked by numerals. Said points, in connection with marks 34 on dial 5, are the reference-marks by which the lock may be operated and 80 85 locked.

The lock is arranged in the following way: Dial 5 being preferably made on plate 6 and casing 7 secured to the inner side of plate 6 hub 25 is then placed in proper place, so that 90 point 27 projects outside of plate 6. Then tumbler 11 is put in place so slot 13 passes over projection 26, when washer 19 and tumbler 15 allow circular slot 17 to pass over projection 26, then washer 23, and tumbler 95 20, so that point 26 engages circular slot 22, after which washer 24 and cover 32 are placed in position and secured together by the bending over of lugs 8 8. Knob 29 is then inserted, so as to allow projection 27 to engage one of the 100

recesses referred to by numeral 28, after which screw and washer 35 are inserted, and the lock is ready for use.

The operation is as follows: The operator having first decided as to what points and numbers he desires to use, which in a lock with three tumblers must be three, and with more tumblers will require more points to be employed, tumbler 11 is placed so that slot 14 registers with hasp 3. Then tumblers 15 and 20 are placed likewise, so slots 18 and 23 register with the hasp. Knob 29 is then placed so that point 27 engages the desired recess in the under side of said knob. Then inserting the hasp, the tumblers may be disarranged by turning the knob, and the lock will be locked. In opening the lock the operator having the combination, which we suppose in this instance is "50"—that is to say, the lock will unlock on the proper point, for instance, number "1" being turned to that number—he turns the knob to the right so "1" registers with "52" on the dial, then to the left so point "1" registers with "43," and then to the right until he registers with "50," when the lock will open.

The combination may be changed at any time by removing screw and washer 35 and place point 27 in another recess. Hence another point may be used, although the same numbers on the dial and the same number of turns must be used, or the same point can be used and different numbers on the dial. The circular slots in tumblers 15 and 20 may be cut out on the same radius and thereby increase the number of locks there may be made with a different combination, as by en-

larging the circular slots in either of the tumblers one degree will make a different combination.

I wish it understood that the parts of this lock may be used for other kinds of locks also without departing from my invention.

Having thus described my invention, what I claim as new, and desire to protect by Letters Patent of the United States, is—

In a combination-lock the combination of a hasp secured to the lid of a chest or trunk a lock placed on the body of a chest or trunk provided with a dial a turning knob, a hub having a projection 26 extending out and turned over at a right angle, three circular tumblers, two of them having circular holes in their centers one having a slot extending from the central circular hole placed on the hub, two of said tumblers being provided with circular slots adjacent to the center hole for receiving the right-angular projection of the hub, three washers having their ends turned out, placed between said tumblers all of said tumblers having a slot cut in their outer edge into which the hasp adapted to pass said hasp being provided with suitable notches for the tumblers, a suitable casing secured to the face-plate provided with lugs by which the cover is secured, substantially as described and shown.

In testimony whereof I affix my signature in presence of two witnesses.

JOHN REUTERBERG.

Witnesses:

JOHN OLSON,
CHAS. M. FLOATHE.
